UNITED STATES PATENT OFFICE.

GEORGE LAGANAS, OF LOWELL, MASSACHUSETTS.

SHOE LEVELING AND SHAPING MACHINE.

Application filed June 5, 1928. Serial No. 282,941.

This invention relates to a shoe leveling and shaping machine for shoe soles and has for its object to provide, in a manner as hereinafter set forth a machine of such class 5 for expeditiously shaping and leveling a shoe sole by the application of pressure after the sole has been attached to the upper thereby resulting in the required bend and curve of the sole to the last.

10 Under the present system in shoe factories, the leveling is accomplished by a direct pressure machine, upon one shoe at a time and as fast as the operator can feed the machine. As the shoe sole is damp and 15 the shoe remains in the machine only a second and is withdrawn still damp, it results that in drying, the sole loses slightly the shape into which it was placed by the machine. This objection is overcome by a machine in accordance with this invention, because when the shoe is removed at the end 20 of the sole leveling operation the sole is dry and will retain the shape imparted thereto.

A further object of the invention is to 25 provide, in a manner as hereinafter set forth, a machine for the purpose set forth whereby the shaping and leveling of the sole is carried out on the original making last, under such conditions providing for increased production and a material decrease in the cost 30 of labor.

A further object of the invention, is to provide a machine of the class referred to 35 whereby it does not necessitate in its use, to accomplish a sole shaping and leveling operation the employment of separate iron beating out forms or lasts, as is the case at present, more especially the employment of different shapes of forms or lasts for 40 different styles and sizes of shoes.

A further object of the invention is to provide, in a manner as hereinafter set forth, a sole leveling and shoe shaping machine which can be employed for all kinds 45 of shoes, such as McKays, welts, etc., for leveling the soles thereof to obtain the required bend and curve on the original making last.

Further objects of the invention are 50 to provide, in a manner as hereinafter set forth, a machine for the purpose referred to which is simple in its construction and arrangement, strong, durable, compact, thoroughly efficient in its use, conveniently operated, readily set up, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a side elevation of a shaping machine in accordance with this invention and illustrating but one of its carriers provided with shaping and leveling means for the sole and with the shoe clamped against said means.

Figure 2 is a fragmentary view in vertical section of the machine.

Figure 3 is a fragmentary view in elevation partly in section of the apparatus.

Figure 4 is a detail section on line 3—3 80 Figure 2.

The machine includes a pair of supporting frames 1, 2 of inverted V-shape and each of which at its upper end is provided with a bearing 3. Rotatably mounted in the bearing 3 is a shaft 4 which can be manually rotated or driven from any suitable means. Spacing collars 11, 12 are fixed to the shaft 4 and abut against the inner faces of the bearings 3.

The shaft 4 is provided with a bore 13 which extends from one end thereof and terminates at a point removed from its other end whereby one end of the bore 13 will be closed. The shaft 4 has that end terminal portion 14 which extends from the frame 1 extending into and secured to a cap member 15 provided with a flange 16 and a socket 17 having a threaded wall with which the terminal portion 14 of the shaft 4 threadedly engages. The cap 15 is furthermore provided with a chamber 18 of the same diameter as the diameter of the bore 13 and the wall of the latter registers with the wall of the chamber 18. The cap 15 is formed with diametrically opposed openings 19, 20 for a purpose to be presently referred to.

Mounted on the cap 15 and abutting against the flange 16 is the head 21 of a coupling member 22 which depends from the cap 15. The head 21 is provided with a concavity 23 with which communicates the

openings 19 and 20. That part of the coupling member 22 which depends from the head 21 is termed a stem 24 and is of tubular form. Detachably connected to the stem 24, 5 as well as communicating therewith, is a fluid pressure feed pipe 25. Preferably air pressure is employed. The head 21 is formed with an axial opening 26 through which extends the cap 15, and the latter 10 projects a substantial distance from the outer side of the head 21 and carries a washer 27 which abuts against the coupling 22. Mounted on the cap 15 and abutting the washer 27 is a coiled spring 28 which functions to maintain the flange 16 against the head 21 of the coupling 22. The spring 28 is maintained in position by a plate 29 and a retaining screw 30 which engages in the cap 15. The shaft 4 intermediate its ends and 20 in proximity to the frame 1 is provided with an opening 31 having a threaded wall and to which is secured a pipe 32 for conducting fluid pressure from the shaft 4 to the point desired.

25 Fixedly secured to the shaft 4 and arranged in spaced relation is a pair of drum heads 33, 33' and each of which is of polygonal contour.

Secured to each drum head is a set of 30 tangentially disposed arms 34 arranged one over the other and with the space between each pair of bars gradually increasing in width outwardly. The arms 34 are secured by holdfast devices 35 against the 35 outer edge of a head 33 or 33'. The set of arms carried by one head are arranged in opposed relation with respect to the arms carried by the other head. Each arm of one set of arms is secured to the opposed 40 arm of the other set of arms by a pair of spaced, combined bracing and supporting bars 37, and secured upon the outer faces of each pair of combined bracing and supporting bars is a set of spaced, rectangular carriers 38. The carriers 38 are arranged in proximity to the outer ends of the arms 34 so as to be in convenient reach of the operator. Secured to each pair of opposed arms is a fluid pressure supply pipe 39 and 45 which is provided with valve controlled branches 40 corresponding in number to the number of carriers of a set, that is to say, if the set of carriers consist of six, the number of valve controlled branches 40 will be 50 the same. A two-way controlling valve for each branch 40 is indicated at 41, and each valve is of a form to establish communication between the said branch and pipe 39, for closing said branch to pipe 39 and for 55 establishing communication between the said branch and the atmosphere when said branch is closed to pipe 39.

The fluid pressure conducting pipe 32 opens into one of the pipes 39. The pipes 60 39 are connected together by branches 39'.

As each branch 40 has a cut-off or controlling valve 41, the branches 40 can be independently employed for supplying pressure to the pressure applying members to be presently referred to.

70

There is to be secured to each carrier 38 a pressure applying element 42 in the form of an inflatable and deflatable bag. Each branch 40 extends through a carrier and communicates with the element 42 for 75 supplying and exhausting fluid pressure to and therefrom.

The shoe 43, with its sole 44 and on its original making last 44', is removably clamped against the member 42. The 80 clamping means for the shoe is indicated at 45, is pivotally connected with a carrier and detachably engages with the outer bar 37.

It is to be understood that the shoe 44 can be clamped against the member 42 by 85 any suitable means. Each branch 40 of a pipe 39 opens into a pressure applying element 42, and the latter is capable of being contracted and expanded, and when expanded by the supply of fluid pressure 90 thereto the element shapes to the shoe which contains the original making last.

The operator places the shoes on the set of carriers facing him and clamps them to the pressure applying elements of the set. 95 The shaft is then rotated to position another set of carriers to have shoes clamped thereon. After the shoes have been placed and clamped against the elements 42 of a set, the branches are opened and fluid pressure 100 supplied to the elements 42 and which acts, in connection with the original making last to level the shoes so that they will assume the desired shape. The shoes remain clamped in the machine under fluid pressure 105 until a set has revolved around from and returned to the operator. The shoes of the set are then removed and another set of shoes placed in position. The shoes of each set remain under pressure until removed, at 110 which time they are dry, under such conditions the soles do not change their shape after being removed from the machine.

The shoe is positioned on a carrier with its original making last. The machine 115 overcomes the necessity of employing iron beating out forms and lasts as they are a great source of expense to shoe manufacturers, further the necessity of purchasing new forms and lasts for every style and size 120 of making last, which becomes obsolete when the style of last goes out of existence, because the leveling action is obtained by the pressure applying members in connection with the shaper elements.

125

In the use of the applicant's machine the sole will dry while under pressure, thereby retaining the shape given thereto, whereas in machines now in general use for such purpose the shoe is removed from the machine 130

while the sole is still wet and under such conditions loses its shape while drying.

It is thought the many advantages of a shoe sole shaping machine in accordance with this invention can be readily understood, and although the preferred embodiment of the invention is as illustrated and described, yet it is to be understood that changes in the details of construction can be had which fall within the scope of the invention as claimed.

What I claim is:

1. A machine for the purpose set forth comprising a bodily rotatable structure including a horizontally disposed shaft, spaced pairs of opposed arms and a set of carriers connected with each pair of opposed arms, said shaft being provided with a bore for communication with a source of fluid pressure, a horizontally disposed, fluid pressure conducting pipe secured to each pair of opposed arms, means for establishing communication between said pipes, a fluid pressure operated shaping and leveling element 25 on each of the carriers of each set, independent, controllable, pressure supply means for each of said elements, said means communicating with said pipes and leading therefrom to said elements, and a fluid pressure conducting pipe leading from said bore to one of said horizontal pipes.

2. A machine for the purpose set forth comprising a bodily rotatable structure including a horizontally disposed shaft, a series of spaced pairs of opposed arms, a pair of bars connecting the arms of each pair together and a set of spaced carriers secured to each pair of bars, said shaft being provided with a bore for communication with a source of fluid pressure, a horizontally disposed, fluid conducting pipe secured to each pair of opposed arms, pipe branches for establishing communication between said pipes, a fluid pressure operated work shaping and leveling element on each of the carriers of each set, independent, controllable, pressure supply means for each of said elements, said means communicating with said pipes and leading therefrom to said elements, and a fluid pressure conducting pipe leading from said bore to one of said horizontal pipes.

3. A machine for the purpose set forth comprising a rotatable, horizontally disposed shaft provided with a bore for communication with a fluid pressure supply, a pair of spaced, vertically disposed heads fixed axially thereof to and bodily movable with said shaft, two sets of opposed arms, the arms of each set secured to and project-

ing from a head, a pair of spaced bars connecting each pair of opposed arms together, a set of spaced carriers secured to each pair of bars, a horizontally disposed, fluid pressure conducting pipe secured to each pair of opposed arms inwardly with respect to the pair of bars, pipe connections for establishing communication between said pipes, a fluid pressure operated work shaping and leveling element on each of the carriers of each set, independent, controllable, pressure supply means for each of said elements, said means communicating with said pipes and leading therefrom to said elements, and a fluid pressure conducting line leading from said bore to one of said horizontal pipes.

4. A machine for the purpose set forth comprising a rotatable, horizontally disposed shaft, said shaft being provided with a bore for communication with a fluid pressure supply, a pair of spaced, vertically disposed, polygonal shaped heads fixed axially thereof to and bodily movable with said shaft, two sets of opposed arms, the arms of each set secured to a head and disposed tangentially with respect thereto, a pair of spaced, combined bracing and supporting bars connecting each pair of opposed arms together, a set of opposed carriers secured upon each pair of bars, a fluid pressure operated work shaping and leveling element on each of the carriers of each set, independent, controllable, pressure supply means for each of said elements, and fluid pressure conducting means leading from said bore and communicating with said supply means.

5. In a machine for the purpose set forth comprising a rotatable, horizontally disposed shaft, said shaft having a bore for communication with a fluid pressure supply, a pair of spaced, vertically disposed heads fixed axially thereof to and bodily movable with said shaft, two sets of opposed arms, each set being secured to and projecting from a head, bracing and supporting means connecting each pair of opposed arms together, a set of opposed carriers secured upon the bracing means between each pair of opposed arms, a fluid pressure operated work shaping and leveling element on each of the carriers of each set, an independent, controllable, pressure supply pipe for each of said elements, and fluid pressure conducting means communicating with said pipes, said fluid pressure conducting means communicating with said bore and connected to said shaft and arms.

In testimony whereof, I affix my signature hereto.

GEORGE LAGANAS.
